DISPLAY SUPPORT

Edward D. Davis, Chicago, Ill., assignor to The
Boye Needle Company, Chicago, Ill., a corpora-
tion of Illinois

Application January 5, 1938, Serial No. 183,527

1 Claim. (Cl. 215—100)

This invention relates to a display support and is particularly useful in the grouping of objects, such as crochet hooks, and a multiple of other objects, in desired separated position, within any ordinary container, such as a glass holder, whereby the sizes of the same can be readily designated.

An object of the invention is to provide a simple device adapted for use with containers of many different types and sizes whereby articles may be conveniently displayed in separated condition, a proper sign therefor being supported by the same. A further object is to provide a simple device adapted for use with containers, such as glass jars, etc., whereby various articles, such as crochet hooks and many other kinds, may be supported in groups, segregated as to size, and in relation with certain size, etc., designations on the device.

20 Heretofore it has been common to supply entire containers for articles, the same being expensive in being adapted to specific things. An object of the present invention is to provide a top member which may be employed with common containers already in use whereby at extremely small expense and effort, an effective display of articles in desired segregated relation is obtained. Other specific objects and advantages will appear as the specification proceeds.

30 The invention is illustrated, in a preferred embodiment, by the accompanying drawing, in which—

Figure 1 is a perspective view of a display support embodying my invention, the same being applied to a glass jar; Fig. 2, a perspective view of the device removed from the glass; Fig. 3, a broken sectional view, the section being taken as indicated at line 3 of Fig. 2; and Fig. 4, a broken rear view of the sign support.

40 In the illustration given, A designates a glass jar or the like; B, the top support member; and C, the sign device.

The glass jar A may be of any type of container which is available and in common use. The support member B, forming my invention, is adapted to be employed with such containers or available jars, etc., as represented by the jar A. The member B comprises a cylindrical cap member 10 having cutaway apertures 11 in its top, thus furnishing cross members 12 and 13. The cross members 13 are provided with grooved portions 14 and upwardly struck metal loops 15 whereby the lower leg portions 16 of the sign shanks 17 are secured to the cap B.

55 Adjacent each of the apertures 11 and aligned

therewith are size inscriptions 18 designating the articles carried within the adjacent aperture.

The sign member C comprises the turned foundation members 16 which engage the metal strips 15, and lie within grooves 14, vertical shank 5 members 17 and the metal sign support 19. The sign support comprises a metal strip having forwardly turned flanges 20 adapted to receive the enclosed information-bearing strip 21. Metal lugs 22 struck from the rear portion of the metal 10 strip 19 engage the upper portion of the shanks 17 so as to support the sign above the cap B.

In the operation of the device, it is only necessary for the merchant to select some available container, such as glass jars, place the cap B 15 thereon and arrange the articles, such as crochet hooks, according to their sizes, within the various apertures. The desired sign insert 21 is then placed within the metal bracket 19. Should the container be broken, or rendered unfit for use, 20 another jar can be readily substituted.

The invention is extremely simple and of very slight cost, while at the same time it provides a very valuable composite product by utilizing ordinary containers, such as glass jars. It provides 25 considerable flexibility by which articles of various types can be readily displayed while housed within cheap and available containers.

It will be understood that the apertures in the top of the cap may be modified in number, 30 size, conformation, etc. Various types of separator bars can be employed. The specific illustration given has been for the purpose of showing one modification and it will be understood that those skilled in the art may change the design 35 thereof and modify the details thereof widely without departing from the spirit of my invention.

The foregoing detailed description has been given for clearness of understanding only, and 40 no unnecessary limitations should be understood therefrom, but the appended claim should be construed as broadly as permissible, in view of the prior art.

I claim:

45 A freely removable container cap adapted to be applied to the open top of containers of various sizes comprising a cap member provided with a substantially flat lower surface for supporting the member on the upper edge of the container, 50 said cap member being equipped with a plurality of sector-shaped apertures in the upper surface thereof and with cross members extending across said cap member between said apertures, the notch portion of said apertures extending to 55

wards the center of the cap member and the ar-
cuate portion adjacent the outer edge thereof
being smooth and integral whereby elongated ar-
ticles extending through said apertures are
5 spread along the outer portion thereof, said cross
members being provided on the upper surface
thereof with means for mounting a sign support,
a sign support having depending legs engaging
said mounting means of said cross members in

interlocking relation, said sign support providing
a slot for the reception of a removable sign, and
an annular depending flange on said cap member
encircling the upper portion of said container,
the portions of said flange adjacent said aper- 5
tures being adapted to receive designating in-
scriptions thereon.

EDWARD D. DAVIS.
